UNITED STATES PATENT OFFICE.

JOSEPH H. SLAKER, OF AURORA, ILLINOIS, ASSIGNOR TO WESTERN WHEELED SCRAPER COMPANY, OF AURORA, ILLINOIS, A CORPORATION OF ILLINOIS.

DUMP CAR.

Application filed September 8, 1923. Serial No. 661,608.

To all whom it may concern:

Be it known that I, JOSEPH H. SLAKER, a citizen of the United States, and a resident of Aurora, in the county of Kane and State 5 of Illinois, have invented certain new and useful Improvements in Dump Cars, of which the following is a specification, reference being had to the accompanying drawings.

10 This invention relates to side-dump cars of the type shown and described in Letters Patent No. 1,357,251, dated November 2, 1920, granted upon the application of Jay B. Rhodes. The invention has for its objects 15 to provide improved and more simple means than there shown for operating the supporting struts to effect a tilting of the car bed; to provide improved means for securing to the rock-shafts that lie beneath the car bed 20 the several arms that project radially from such shafts, and to improve generally the construction and operation of devices of this general character. That which I believe to be new is set forth in the claims.

25 In the drawings,

Fig. 1 is a transverse section through a dump car bed at a point approximating its longitudinal center and illustrating, in connection with the power means by which a 30 tilting of the car bed is effected, the improved means for securing the locking arms to their respective rock-shafts;

Fig. 2 is an enlarged detail being a perspective view of one of the locking arms and illustrating the means employed for connecting it to its rock-shaft;

Fig. 3 is a transverse section through the car bed taken near one end thereof and illustrating the struts that support each side of 40 the car, and also the improved means through which said struts are moved when the car bed is to be tilted, the strut at the right-hand side of the figure and the means that act upon it being shown in the position 45 they assume at the time the power means are in the position shown in Fig. 1;

Fig. 4 is a plan view of the means through 50 which the supporting struts are operated to effect a tilting of the car bed, the struts being in section;

Fig. 5 is a view similar to Fig. 3 but showing the parts in the position they assume when the car bed has been tilted and the power means that has caused the tilting 55 has been returned to normal position; and

Fig. 6 is a detail of one of the arms carried by each rock-shaft for engaging and rocking the member that is pivoted on the other rock-shaft to effect a movement of the strut with which such member is connected. 60

Referring to the several figures of the drawings,—10 indicates a car bed pivoted centrally at different points, as at 11, throughout its length to heavy brackets, such as shown at 12, that rise from and are 65 secured to an ordinary under-body that preferably comprises a pair of spaced-apart longitudinal I-beams 13. Near the longitudinal center of the car and on opposite sides, respectively, of the said beams 13 are 70 located two cylinders 14 adapted to be supplied with compressed air, as usual, so as to force up alternatively the plungers 15 in said cylinders that carry the laterally-movable plunger-rods 16, each plunger-rod having 75 pivotally connected to its upper end, as at 18, a curved bar 17 that at its other end is pivotally connected at 19 to a central support or bracket 20 carried by the beams 13, as shown in Fig. 1. The rounded head of 80

each plunger-rod is adapted, when such rod is forced up, to engage with the recess 21 in the lower end of the lower member 22 of a thrust bar, the other member of which thrust bar is indicated by 23 and is pivoted 85 to the car bed at 24,—the two members of each thrust bar being pivoted together at 25, and the thrust bar as a whole being held in proper position to be engaged by its coacting plunger-rod by a bar 26 secured in place 90

at its inner end upon the pivot 19 and being attached at its other end by a pivot 27 to the lower member 22 of the thrust bar. The construction and operation of the parts so far briefly referred to are in all substantial 95 respects like the corresponding parts in the said Rhodes patent and it is therefore not deemed necessary to describe them more in detail.

28 indicates two rock-shafts mounted in 100 suitable bearings carried by the under-body, said shafts being arranged parallel with each other and on opposite sides, respectively, of the longitudinal center of the body. As in said patent there is secured 105 upon each shaft so as to rock therewith an arm which by bearing at its free end against a member of the under-body will act to prevent rotation in one direction of the shaft to which it is attached, but by reason of the 110

engagement with such arm of a latch pivotally mounted on the adjacent curved bar 17 may be swung out of locking position when such bar is moved up. Each of the said locking arms is indicated by 29 and the respective latches by 30. Both with respect to the manner of attachment to its rock-shaft and in its construction to adapt it for engagement with its latch each of these locking arms 29 differs from the corresponding part in the said Rhodes patent. In that patented construction each rock-shaft was square in cross-section, or at least that portion was so shaped that carried the locking arm. I avoid the necessity of squaring that portion of the cylindrical rock-shaft and of forming a correspondingly-shaped eye in the locking arm by forming in one face of the locking arm a notch 31 (see Fig. 2) into which the cylindrical rock-shaft fits, the two parts being clamped together by a U-bolt 32 upon the ends of which are screwed nuts 33. Relative rotation of the parts is prevented by a key 34. The free end of the arm 29 has a laterally-extending member 29^a which, as shown in Fig. 1, lies behind the latch 30, which in its edge and near its lower end is hook-shaped to receive and engage with this turned member 29^a. So forming the arm avoids the necessity of providing it with a separate pin for the latch to engage with and therefore is not only cheaper to construct but is a stronger construction than where such a pin was used, as was the case in said patented construction.

Toward each end of the car and at equal distances from the transverse center thereof are employed, as in the said patent, two jointed or toggle-lever strut devices, each of which devices, as shown in Fig. 4, I prefer to make of two spaced-apart sets of similar jointed members, the upper member of each set being indicated by 35 and the lower one by 36, the inner ends of the parts 35 and 36 being pivotally mounted on a heavy pin 37. The upper end of each toggle member 35 is pivoted at 38 to the car bed and the lower end of each toggle member 36 is pivotally connected at 39 to the outer end of a bar 40, the other ends of which bars 40 are pivotally attached at 41 to a portion of the under body—the construction being quite similar to that shown in the said patent. In that patented construction, however, there was employed a rigid locking bar for each strut device which at its outer end was pivotally attached to the strut at a point below the joint in the strut and at its inner end was connected to a rocking lever mounted on a pivot separate from and in a higher plane than the said rock-shafts, and, through a system of links and levers interposed between the said rocking lever and the rock-shafts the turning

of one of the rock-shafts would cause such a pull upon the proper one of the long locking bars connected with the struts as to break the toggle-like strut that such bar was connected with, so as to thereby effect 70 a tilting of the car bed. I have devised a very much simpler arrangement of parts for accomplishing the supporting and breaking of each of the toggle-like struts. In my improved construction the locking bar 75 is itself formed of two members jointed together to form a toggle device, the outer and inner members being indicated respectively by 42 and 43 and the pivot connecting such parts together being indicated by 80 44. The outer member 42 is preferably formed of branches that diverge from the pivot 44, as shown in Fig. 4, the end portions of which are journaled upon the heavy pivot 37. The inner member 43 of each 85 toggle-like locking bar is journaled upon the adjacent rock-shaft 28, the inner end portion of such inner member extending past such rock-shaft to a point closely adjacent to the other rock-shaft (see Figs. 3 90 and 4) when said locking bar is in its locking position. As shown in Fig. 4 the outer members 42 of the two locking bars are so shaped as to position the inner members 95 out of alignment with each other, thus providing for the attachment to each rock-shaft of an arm that will overlie the projecting inner end of the locking bar member 43 that is journaled upon the other rock-shaft. Each of these overlying arms is 100 indicated by 45, and, as best shown in Fig. 6, it has a curved groove in its under face 105 in which fits the cylindrical rock-shaft, the parts being held together by a U-bolt 46 embracing the shaft and passing through the arm and nuts 47 screwed on the ends of the bolt. As in the case of the arms 29 that are carried by these same rock-shafts, a key, indicated by 48, is employed to prevent relative rotation between each arm 45 and the 110 shaft upon which it is mounted. In Fig. 1 the plunger rod 16 at the left hand side of that figure is shown as having been raised sufficiently to engage with the jointed thrust bar at that side of the 115 car, such upward movement of that plunger rod having of course turned the curved bar 17 that is connected with it so as to carry up its latch 30 and the locking arm 29 that such latch engages. That locking arm being 120 non-rotatably connected with its rock-shaft causes a turning of the rock-shaft in clockwise direction as viewed in Fig. 1 with the result that the other arm 45 that is also affixed in like manner to that rock-shaft is turned 125 down and forced against the underlying projecting end portion of the locking bar member 43 that is pivotally mounted on the other rock-shaft, such turning, of course, causing a breaking of the toggle-lever de- 130

vice of which that said member 43 is a part, and necessarily also breaking the toggle-like strut device with which said other toggle device is connected, as shown in full lines at 5 the right-hand side of Fig. 3. Such breaking of these toggle devices permits the tilting into dumping position of the car bed as shown in Fig. 5. In that figure the arm 10 45 that had been rocked down as shown in Fig. 3 is shown as restored to normal horizontal position due to the retraction of the plunger and its piston that had been operated to effect the tilting. The operation of 15 the parts for effecting a tilting of the car bed toward the opposite side will be obvious from the description given, and a description of the manner of effecting a righting of the bed is deemed unnecessary as it is fully set forth in the said Rhodes patent. The 20 free end of each arm 43 is rounded as shown so as to move easily over the surface of the locking bar member 43 that it engages.

By my improvements I dispense with a considerable number of parts that were heretofore deemed necessary, as shown by 25 said patent, for accomplishing the moving or flexing of the supporting struts and am able to apply with equal effectiveness and much more directness the power from one of the 30 rock-shafts to the supporting strut device at the opposite side of the car.

What I claim as my invention and desire to secure by Letters Patent, is—

1. A dump car comprising in combination 35 a car bed, a support therefor with which said bed is pivotally connected to adapt it for tilting in opposite directions alternatively, a laterally-movable strut under the car bed near each side thereof, two parallel 40 rock-shafts extending longitudinally of and beneath said bed, two locking bars pivotally mounted on said rock-shafts, respectively, and each connected with one of said struts, means carried by each rock-shaft adapted, 45 when the rock-shaft is turned, to engage and turn the locking bar that is pivotally mounted on the other rock-shaft, and means for rocking either of said rock-shafts.

2. A dump car comprising in combination 50 a car bed, a support therefor with which said bed is pivotally connected to adapt it for tilting in opposite directions alternatively, a toggle-lever strut under the car bed near

each side thereof, two parallel rock-shafts extending longitudinally of and beneath 55 said bed, a toggle-lever locking bar connected with each of said struts, the inner member of each of said locking bars being pivotally mounted on one of said rock-shafts and having its inner end portion projecting 60 toward the other rock-shaft, means carried by each rock-shaft for engaging the said projecting inner end portion of the locking bar that is pivotally mounted on the other rock-shaft, and means for rotating either of 65 said rock-shafts.

3. A dump car comprising in combination a car bed, a support therefor with which said bed is pivotally connected to adapt it for tilting in opposite directions alternatively, 70 two parallel rock-shafts beneath said bed, two laterally-movable struts arranged respectively beneath and adjacent to opposite sides of the bed, a bar pivotally connected with each strut and pivoted on one of said rock-shafts, each bar comprising two members pivoted together and the inner member of each having an end portion projecting toward the other one of said rock-shafts, an arm non-rotatably mounted on each rock- 80 shaft and lying over and adapted to be brought in contact with the said projecting end portion of the inner member of the bar mounted on the other rock-shaft, and means for rocking either of said rock-shafts. 85

4. The combination with a car bed and means for tilting the same, said tilting means including a cylindrical rock-shaft having an arm provided with a notch in which said shaft fits, of a U-bolt embracing 90 said shaft and passing through said arm, nuts on said bolt for holding said parts together, and means for interlocking said shaft and arm to prevent relative rotation.

5. The combination with a car bed and means for tilting the same, said tilting means including a cylindrical rock-shaft having an arm provided with a notch in which said shaft fits, of a U-bolt embracing 95 said shaft and passing through said arm, nuts on said bolt for holding said parts together, and a key interposed between said shaft and arm for preventing relative rotation of the parts. 100

JOSEPH H. SLAKER.
